UNITED STATES PATENT OFFICE.

JOHN L. DUNNOCK, OF BALTIMORE, MARYLAND.

BOTTLE-CLOSURE.

1,158,462.

Specification of Letters Patent.

Patented Nov. 2, 1915.

Application filed February 5, 1915. Serial No. 3,222.

To all whom it may concern:

Be it known that I, JOHN L. DUNNOCK, a citizen of the United States, residing at Baltimore city, State of Maryland, have invented certain new and useful Improvements in 5 Bottle-Closures, of which the following is a specification.

This invention is in the nature of a bottle stopper or closure and has for its object to 10 provide a device of the character specified which will be economical to manufacture, easily and quickly placed upon or removed from the bottle, effective in closing the bottle and not easily breakable. 15 With this object in view, the invention consists in the construction, arrangement and combination of the parts of a bottle closure which will be hereinafter fully described and afterward specifically claimed. 20 In order that the construction and operation thereof may be readily comprehended, I have illustrated an approved form and a modification thereof in the accompanying drawings, and will now proceed to specifically describe the same, having reference to 25 said drawings in which—

Figure 1 represents a view in elevation of a bottle having my improved stopper in position thereon. Fig. 2 represents a sectional view taken on a plane cutting vertically through the upper part of the bottle and the stopper, the main body of the bottle being shown in elevation. Fig. 3 represents a transverse sectional view taken on the plane 30 indicated by the broken line 3—3 in Fig. 1, looking downward. Fig. 4 represents a sectional view through the upper part of a bottle and a stopper thereon of modified form, the main body of the bottle being broken 35 away.

Like reference characters indicate the same parts wherever they appear in a plurality of the figures of the drawings.

Referring specifically to the drawings, 5 indicates the body of a bottle of any desired form which is provided with a mouth or neck 6, of the usual substantially cylindrical form.

Referring to Figs. 1, 2 and 3, my stopper comprises a main body 7 from which de-

pends a cylindrical flange 8 adapted to fit closely over the neck 6. Within the cylindrical depending flange 8 of the stopper, and centrally located therein, is a depending central projection 9, shorter than the depending flange 8, around which is fitted a cup-shaped cork 10 of the same length as the depending flange 8 and of a diameter to snugly fit within the neck 6 of the bottle.

The outer surface of the neck of the bottle 60 and the inner surface of the depending rigid flange 8, which surfaces contact with each other in closing the bottle, are preferably ground in order to afford a close, non-leakable joint. When the stopper thus described 65 is placed upon the bottle the cork 10 fits closely within the neck of the bottle and the depending flange 8 fits closely around the neck of the bottle and thus a tight, secure, 70 non-leakable closure is effected.

In the modification shown in Fig. 4, the main body 5 and the neck 6 of the bottle, and the main body 7 and the depending flange 8 of the stopper are identical with those of the other figures hereinbefore described. 75 In this modification, however, the cork 10 is omitted and a central projection 90 is substituted for the projection 9, said projection 90 being of substantially the same length as the flange 8 and of a size to 80 snugly fit within the neck of the bottle, the outer surface of the flange 90 and the inner surface of the flange 8, as well as both the inner and outer surfaces of the neck of the bottle being ground to afford a close, non- 85 leakable joint.

The construction, operation, and utility of the invention will be readily understood from the foregoing and while the exact construction has been hereinbefore specifically 90 described it will be obvious to those skilled in the art to which the invention most nearly appertains that many slight changes and variations may be made without departing from the spirit and scope of the invention as 95 hereinafter claimed.

Having thus fully described my invention, what I claim as new and desire to secure by United States Letters Patent is,

A bottle stopper, comprising a main body 100

having two concentric depending portions forming a bottle-neck receiving groove, one of said depending portions being compressible and the other rigid, said rigid portion having a ground inner face to form a sealing face to engage the exterior of the bottle-neck, and said compressible portion adapted to form a seal with the interior of the bot-

tle-neck and allow the seating of the rigid portion.

In testimony whereof I affix my signature
in presence of two witnesses.

JOHN L. DUNNOCK.
